CLAIM

The ornamental design for a camera module as shown and described.

DESCRIPTION

FIG. 1 is a top, front perspective view of a camera module of the present disclosure;

FIG. 2 is a top, rear perspective view of the camera module of FIG. 1;

FIG. 3 is a front elevational view of the camera module of FIG. 1;

FIG. 4 is a rear elevational view of the camera module of FIG. 1;

FIG. 5 is a first side elevational view of the camera module of FIG. 1;

FIG. 6 is a second side elevational view of the camera module of FIG. 1;

FIG. 7 is a top plan view of the camera module of FIG. 1; FIG. 8 is a bottom plan view of the camera module of FIG. 1;

FIG. 9 is a top, front perspective view of a camera module of the present disclosure;

FIG. 10 is a top, rear perspective view of the camera module of FIG. 9;

FIG. 11 is a front elevational view of the camera module of FIG. 9;

FIG. 12 is a rear elevational view of the camera module of FIG. 9;

FIG. 13 is a first side elevational view of the camera module of FIG. 9;

FIG. 14 is a second side elevational view of the camera module of FIG. 9;

FIG. 15 is a top plan view of the camera module of FIG. 9; and,

FIG. 16 is a bottom plan view of the camera module of FIG. 9.

(Continued)

The broken lines depict portions of the camera module that forms no part of the claimed design.
